CLIMBING ATTACHMENT FOR SKIS

Jerome E. Barieau, Auburn, Calif.

Application February 12, 1935, Serial No. 6,161

9 Claims. (Cl. 208—184)

This invention relates to skis and particularly to attachments for the same by means of which a non-slipping grip on the snow may be obtained such as is of great assistance in climbing, as well as to prevent side slipping on icy surfaces.

The principal object of my invention is to provide an attachment of this character, which includes cleats made right and left for the corresponding skis, adapted to be removably mounted on the skis adjacent the boot clips where their use is most effective; and so constructed and mounted that they may be easily and quickly shifted from position for climbing to one for gliding or when they are out of the way and non-effective.

A further object is to arrange the non-skid cleats so that when they are in operative position they extend directly across and under the skis in clearance relation both to the bottom and side edges thereof. By reason of this construction and on account of the fact that the cleats are located immediately adjacent the boot clips, or where the weight is on the skis, there is no chance for the snow to adhere to and pack between the skis and cleats, and the cleats will always engage the snow where it is well packed and a positive firm grip on the snow is obtained as is necessary.

30 A further object is to provide a simple and easily operated catch means for holding the detachable cleats in either position on the skis.

A further object of the invention is to produce a simple and inexpensive device and yet one 35 which will be exceedingly effective for the purpose for which it is designed.

These objects I accomplish by means of such structure and relative arrangement of parts as will fully appear by a perusal of the following 40 specification and claims.

In the drawing similar characters of reference indicate corresponding parts in the several views:

45 Figures 1 and 2 are fragmentary perspective outlines of a right foot ski showing my attachment mounted thereon in position for climbing and gliding respectively.

Figure 3 is a fragmentary side outline of a ski and its boot clip showing the position of the 50 non-slip cleat relative thereto.

Figure 4 is a longitudinal section of the attachment as mounted on a ski.

55 Figure 5 is a cross section of a ski back of the attachment, showing the cleat in operative position.

Figure 6 is a top plan view of the attachment partly broken out.

Referring now more particularly to the characters of reference on the drawing, the attachment comprises an anchor plate 1 secured on the upper face of the ski 2 immediately adjacent and in front of the boot clip 3. The anchor plate is arched upwardly intermediate its ends to form, with the upper surface of the ski, a rectangular transversely extending slot 4. The slot is adapted to receive a tongue 5 formed with and bent at right angles to a plate 6 which depends from the outside of the ski in clearance relation to the side edge thereof and forms the cleat supporting bracket. Extending across the ski and bent from the front edge of the plate 6 below and in clearance relation to the bottom surface of the ski is a rectangular plate 7 forming the non-slip cleat itself. This cleat extends the full width of the ski and is preferably somewhat deeper than the thickness of the same.

The plate 6 besides serving as a cleat supporting bracket, is of sufficient width to serve another important function. Its relatively great width, extending lengthwise of and below the ski when the cleat is in operative position, acts to efficiently prevent side slipping, so that the device is of service in giving traction in side hill and up hill work.

30 The tongue 5 is removably held in place in the anchor plate by a spring pressed bevel latch bolt 8 engaging a notch 9 cut in the front side edge of the tongue. The bolt is slidably mounted in connection with the anchor plate and a housing 10 secured on top of said plate in front of the slot 4. It is withdrawn from engagement with the notch when desired to remove the tongue by means of a finger clip member 11 attached to the bolt and projecting forwardly and then upwardly from in front of the front end of the housing. When the tongue is in the above described position therefore it is held against displacement in the anchor plate and the cleat is maintained in an effective operating position under and yet clear of the ski.

45 When it is desired to dispose the cleat in an inoperative position as when using the skis for gliding, the tongue is withdrawn from the anchor plate and the cleat, which is the same width as the tongue, is inserted in the slot 4 in its place. The cleat is thus raised above the ski, while at the same time being housed and protected and the tongue then extends vertically and transversely of the ski in front of the anchor plate, as shown in Figure 2. With this positioning of 50 55

the cleat device it is unnecessary to hold the cleat latched against removal since there is no strain on the same and the pressure of the edge of the latch bolt against the side edge of the cleat is sufficient to hold the same in place.

5 The cleat and bracket unit being removable from the anchor plate may be placed in the knapsack or left behind at times, as when the skier intends to practice jumping for instance.

10 From the foregoing description it will be readily seen that I have produced such a device as substantially fulfills the objects of the invention as set forth herein.

15 While this specification sets forth in detail the present and preferred construction of the device, still in practice such deviations from such detail may be resorted to as do not form a departure from the spirit of the invention; as defined by the appended claims.

20 Having thus described my invention, what I claim as new and useful and desire to secure by Letters Patent is:

25 1. A climbing attachment for a ski comprising a cleat to extend transversely of and under the ski, and means to rigidly mount the cleat in operative position substantially at right angles to the bottom surface of the ski intermediate the ends of the ski and so that a clear space is left between the upper edge of the cleat and 30 the bottom surface of the ski.

35 2. A climbing attachment for a ski comprising a cleat to extend transversely of and under the ski, a bracket plate projecting upwardly from one edge of the cleat at right angles thereto and outwardly of one side of the ski in spaced relation thereto, a tongue projecting transversely of the ski from the top of the bracket plate, and an anchor plate secured on the top of the 40 ski and formed with a recess extending transversely of the ski to slidably and non-turnably receive the tongue.

45 3. A structure as in claim 2, in which the tongue and cleat are interchangeable in position in the recess.

45 4. A nonslip attachment for a ski comprising as a unit, a vertical cleat below and extending transversely of the ski substantially at right angles to the bottom surface thereof when in an operative position, and a bracket supporting 50 the cleat from the ski and comprising a plate depending from the top and down one side of the ski to the bottom of the cleat and extending lengthwise of the ski; both the plate and cleat being disposed to leave a clear space between

the side and bottom respectively of the ski whereby to prevent packing of snow between the ski and attachment.

5 5. A climbing attachment for a ski comprising a cleat to extend transversely of and under the ski, a bracket plate projecting upwardly from one edge of the cleat outwardly of one side of the ski, an element on the upper end of the plate to extend transversely of the ski above the same, and supporting means mounted on the upper surface of the ski to directly engage and hold said element rigidly in place.

10 6. A climbing attachment for a ski comprising a cleat to extend transversely of and under the ski, a bracket plate projecting upwardly from one edge of the cleat outwardly of one side of the ski, a member mounted on the upper surface of the ski, and means formed with the cleat on one side of the same for removable supporting engagement with said member.

15 7. A climbing attachment for a ski comprising a cleat adapted when in operative position to extend transversely of and under the ski, and means between the upper surface of the ski and the cleat to hold the cleat rigidly in said operative position or maintain the same in a non-movable position above the ski, selectively.

20 8. A climbing attachment for a ski comprising a cleat to extend transversely of and under the ski, a bracket plate extending upwardly from one edge of the cleat and outwardly of one side of the ski, an anchor plate secured on the top of the ski and providing a non-circular recess extending transversely of the ski and open to said one side, and an element on the bracket plate to slidably but non-turnably enter the recess.

25 9. A climbing attachment for a ski comprising a cleat to extend transversely of and under the ski, a bracket plate extending upwardly from one edge of the cleat and outwardly of one side of the ski, an anchor plate secured on the top of the ski and providing a substantially rectangular recess extending transversely of the ski and open to said side and whose major width extends lengthwise of the ski, a tongue on the bracket plate to slidably fit in the recess, one side edge of the tongue having a notch, and a releasable latch mounted on the anchor plate to engage the notch when the tongue is in place and movable at right angles to the tongue to withdraw from the notch.

40 45 50 JEROME E. BARIEAU.
